Primary Examiner — Lucy Lieberman*(74) Attorney, Agent, or Firm* — Foley & Lardner LLP(57) **CLAIM**

I claim the ornamental design for a combined watch dial and hands, as shown and described.

DESCRIPTION

FIG. 1 is a front elevation view of a combined watch dial and hands of the claimed design; and,

FIG. 2 is a front and right side perspective view of the combined watch dial and hands.

The ornamental design which is claimed is shown in solid lines in the drawings.
